Inventor:

Irvin R. Miller
By his Attorneys,

Williamson Merchant

UNITED STATES PATENT OFFICE.

IRVIN R. MILLER, OF ST. PAUL, MINNESOTA.

PORTABLE PROPELLING DEVICE FOR BOATS.

SPECIFICATION forming part of Letters Patent No. 712,081, dated October 28, 1902.

Application filed September 20, 1901. Serial No. 75,789. (No model.)

To all whom it may concern:

Be it known that I, IRVIN R. MILLER, a citizen of the United States, residing at St. Paul, in the county of Ramsey and State of Minnesota, have invented certain new and useful Improvements in Portable Propelling Devices for Boats; and I do hereby declare the following to be a full, clear, and exact description of the invention, such as will enable others skilled in the art to which it appertains to make and use the same.

My invention has for its object to provide an improved detachable motor for propelling row-boats; and to this end it consists of the novel devices and combinations of devices hereinafter described, and defined in the claim.

The invention is illustrated in the accompanying drawings, wherein like characters indicate like parts throughout the several views.

Figure 1 is a view in elevation showing a row-boat having my improved detachable motor applied to the stern end thereof, parts of the motor-case being broken away. Fig. 2 is a side elevation of the parts shown in Fig. 1, parts of the boat and of the motor-case being broken away; and Fig. 3 is a detail in horizontal section taken on the line x^3 of Fig. 1.

The numeral 1 indicates the row-boat, which is of ordinary construction, provided at its stern end with the skeg 2 and stern-board 3.

In accordance with my invention I mount the motor in a shell or case which follows approximately the outline of the stern of the boat and is adapted to be partially submerged in the water. This case at its lower portion is water-tight, so that it is given considerable buoyancy. This feature is important, as the increased buoyancy given to the stern end of the boat assists in holding up the stern end of the boat regardless of the added weight of the motor. At its top this case is shown as provided with a hinged cover a' , which may be readily raised to afford access to the interior of the case.

For detachably and adjustably securing the case a to the stern of the boat it is provided with a pair of laterally-spaced and vertically-adjustable hangers b , which work in channel-

like keepers b' on the interior of the case a . Set-screws b^2 , which work through the hangers or brackets b and impinge on the backs of the keepers b' , serve to hold said hangers in the desired set adjustments. The upper ends of the hangers b are bent forward and then downward, so as to afford hooks, which are adapted to be engaged over the upper edge of the stern-board 3, as best shown in Fig. 2. Set-screws c , preferably having knurled heads, work through the depending hooked ends of said hangers b and when screwed into or against the said board securely anchor the said hangers thereto.

At its lower forward portion the motor-case a is provided with laterally-spaced ears d , which are adapted to embrace the adjacent portion of the skeg 2. Set-screws d' , preferably having knurled heads, work through the ears d and impinge against the skeg 2 to securely anchor the lower portion of the case a to the boat. Thus the case a is detachably secured to the stern of the boat and is adapted to be vertically adjusted so as to bring the propeller, presently to be noted, to the proper depth in the water.

I employ a gasoline or explosive engine for producing the motive power, and the parts thereof are mounted within the case a . This explosive-engine may take various forms, and for the purposes of this case the parts thereof may be briefly noted.

f^1 indicates the cylinder, and f^2 the piston, of the engine, the former of which is rigidly secured to the front plate of the case a .

f^2 indicates the propeller-shaft, which is suitably mounted in bearings f^3 and f^4 of the case a and is provided at its rear outer end with an ordinary reversible propeller f^5 .

f^6 indicates a spur-pinion on the propeller-shaft f^2 , and f^7 indicates an intermeshing spur-gear loosely mounted on the bearing f^4 . The piston f^2 is connected to a crank-pin f^8 on the gear f^7 by means of a pitman or rod f^9 . The crank-pin f^9 projects so as to afford a handpiece by means of which the engine may be started.

g indicates an ordinary propeller-reversing lever which, as shown, projects upward above the top of the case a and works through a suitable passage (not shown) in the lid a' .

K indicates the oil-tank.

m indicates the battery of the igniter.

n indicates the exhaust-pipe from the engine, and p indicates the oil-supply pipe to the engine, all of which parts are within the case a and are of the ordinary construction.

Other details of the engine, which may be of any suitable construction, are not herein illustrated, nor is it necessary for the purposes of this case.

I believe I am the first to provide a detachable device involving an explosive-engine adapted for propelling row-boats when applied to the stern thereof, and I also believe that I am the first to provide in connection with a motor of any kind a hollow air-containing motor-case which when submerged or partially submerged adds buoyancy to the stern end of the boat, and thus serves to support

or partially support the weight of the motor 20 and propelling devices.

What I claim, and desire to secure by Letters Patent of the United States, is as follows:

The combination with an engine or motor 25 and a support for the same, of a clamping device for securing said support to the stern of the boat which clamping device is vertically adjustable with respect to said support, and a propeller having its shaft mounted in 30 said support and driven from said engine or motor, substantially as described.

In testimony whereof I affix my signature in presence of two witnesses.

IRVIN R. MILLER.
